(57) **CLAIM**

The ornamental design for baseball headwear, as shown and described.

DESCRIPTION

FIG. 1 is an perspective view of the present invention;

FIG. 2 is a front view of the present invention;

FIG. 3 is a side view of the present invention;

FIG. 4 is a back view of the present invention;

FIG. 5 is a top view of the present invention; and,

FIG. 6 is a bottom view of the present invention.

The broken-line boundaries shown in FIGS. 1, 2 and 6 illustrate the bounds of the claimed design.
